DRAUGHT BEER CONTROLLING UNIT

Fred C. Bristol, Chicago, Ill., assignor to Herman
M. Gumbin, Chicago, Ill.

Application June 23, 1939, Serial No. 280,886

3 Claims. (Cl. 225—9)

This invention relates to a draught beer controlling unit.

The object of the invention is to provide, in a manner as hereinafter set forth, a unit of the class referred to for interposition in a beer dispensing line and acting to maintain an even or uniform beer on the dispensing of the latter.

A further object of the invention is to provide, in a manner as hereinafter set forth, a unit of the class referred to acting to overcome wild beer conditions on the dispensing of the beer, whereby the vending of the draught beer is simplified and free of waste at a very nominal cost.

A further object of the invention is to provide, in a manner as hereinafter set forth, a unit of the class referred to for interposition between the cooling coils and faucet of a beer dispensing line to overcome the formation of air pockets in the beer thereby providing a smooth beer and which by virtue of the beer pressure is forced along directly to the faucet and dispensed in an even or uniform condition.

Further objects of the invention are to provide, in a manner as hereinafter set forth, a unit for the purpose referred to which is simple in its construction, strong, durable, compact, thoroughly efficient in its use, readily assembled, automatic in its action, conveniently interpositioned in a beer dispensing line in juxtaposition to the opening or faucet of such line, and inexpensive to manufacture.

Embodying the objects aforesaid and others which may hereinafter appear, the invention consists of the novel construction, combination and arrangement of parts as will be more specifically referred to and illustrated in the accompanying drawing, wherein is shown an embodiment of the invention, but it is to be understood that changes, variations and modifications may be resorted to which fall within the scope of the invention as claimed.

In the drawing:

Figure 1 is a top plan view partly broken away showing the adaptation of the controlling unit in accordance with this invention installed with respect to a beer dispensing line, the faucet and cooling coils of the line being shown in dotted lines.

Figure 2 is a section on line 2—2, Figure 1, and

Figure 3 is a section on line 3—3, Figure 1.

With reference to the drawing the unit includes an open top and closed bottom housing 1 preferably of flared contour. There is associated with the housing 1 a removable closure 2 for the

open top of the housing 1. Preferably the latter will be of flared contour, but it is to be understood that the contour of the housing 1 may be as desired. The housing 1 in proximity to its upper end is formed with an intake opening 3 for the beer as it leaves the coil 4 of the dispensing line 5. Integral with the outer surface of the housing 1 is a laterally extending tubular nipple 6 having its inner diameter corresponding to the diameter of the opening 3. The inner face of the nipple 6 forms an outward continuation of the wall of the opening 3. The nipple 6 is peripherally threaded as at 7 and a suitable means, such as indicated at 8 is employed for coupling the line 9 to the nipple 6. The housing 1 diametrically opposite the opening 3 is formed with an opening 9 of materially less diameter than the opening 3. Formed integral with the outer surface of the housing 1 diametrically opposite the nipple 6 is a laterally extending peripherally threaded tubular nipple 10. The inner face of the nipple 10 is formed of a portion of uniform diameter, as indicated at 11 and a flared portion as indicated at 12. The diameter of the portion 11 corresponds to the diameter of the opening 9 and it forms a continuation of the wall of said opening 9. The flared portion 12 merges into the outer end of the portion 11 and terminates on the outer end of the nipple 10. The largest diameter of the flared portion 12 is less than the diameter of the opening 3. The upper terminal portion 13 of the housing 1 is of greater thickness than the remaining portion of the body of the housing. There is formed integral with the portion 13 on the outer marginal part thereof a vertically disposed annular flange 14. That part of the portion 13 inwardly of the flange 14 provides a seat 15 for a purpose to be referred to. The housing 1 at its upper end is formed with a plurality of radially disposed spaced lugs 16 formed with vertically disposed threaded openings 17 in proximity to their outer ends. The outlet or faucet of the line 5 is indicated at 18, which is carried by part 19 of the line 5 and such part 19 is coupled to the nipple 10 by any suitable means, such as indicated at 20. The faucet 18 is arranged in close proximity to the nipple 10, if desired, however the faucet 18 may be connected directly to the nipple 10.

The closure 2 not only constitutes means for closing the upper end of the housing 1, but also provides a support for a valve structure 21 and a suspension for the valve 22 of the structure 21 and for a float controlled operating mechanism 23 for the valve 22. The closure 2 consists of a cir-

cular body part 24 of arcuate contour in diametrical section. The body part 24 in its lower end is formed with an outwardly directed annular enlargement 25 having an annular flange 26. The 5 enlargement 25, when the closure 2 is in position is adapted to be surrounded below its flange 26 by the flange 14. There is mounted on the seat 15 an annular sealing gasket 26a upon which the enlargement 25 bears when the closure 2 is in 10 its closing position relative to the housing 1. The body part 24 of closure 3 has formed integral with its top surface radially disposed arms 27 formed with vertical openings 28 in proximity to their outer ends. The arms 27 are to align with 15 the lugs 16 and the openings 17 are to align with the openings 28. Extending through the openings 28 and threadably engaging with the openings 27 are holdfast means in the form of headed screws 29 acting to connect the closure 2 and the 20 housing 1 and clamp the enlargement 25 against the gasket 26a.

The closure 2 is formed with an enlargement 30 and also with a vertically disposed threaded opening 31 which extends through the enlargement 30 and the body part 24 and communicates with the interior of the closure 2. Threadably engaging with the wall of the opening 31 is a peripherally threaded tubular stem 32 of a valve seat forming block 33. The lower end of the stem 30 forms a valve seat 34 for the upper end of 35 the valve 22. The block 33 has a vertically disposed threaded opening 35 terminating at its lower end in a tapered valve seat 36 for a needle valve 37 which threadably engages with the wall of the opening 35. The block 33 has a horizontally disposed air outlet 38 which leads from the seat 36. The block 33 is formed with a vertical opening 39 forming a continuation of the inner face of the stem 32 and leading to the seat 36. 40 Integral with the inner face of the body part 24 of the closure 2 is a pair of depending spaced parallel hangers 40 between which extends one end of a lever arm 41. The latter is pivotally connected to the hangers 40, as at 42 and also pivotally connected, as at 43 to the lower end of 45 the valve 22. The lever 41 is somewhat torsionally twisted and it is formed integral with a globular float 44, as at 45. The valve 22 has extending from its upper end a stem 46 which is slidably mounted in the stem 32.

The housing 1 provides a chamber 47 for receiving the beer from the coil 4 through the means of the nipple 6 and intake 3. Arranged within the chamber 47, as well as extending into and secured to the nipple 10 is a beer conducting-off element 48 of a form to provide for restricted discharge of the beer from the chamber 47. The element 48 is in the form of a coiled tube 49 having its inner diameter materially less than the 55 diameter of the intake 3 and the inner diameter of the dispensing line 5. The tube has a portion thereof, indicated at 50 extended through the opening 9 and into the nipple 10. The outer end of the portion 50 is flared to conform to the 60 part 12 of the inner face of the nipple 10. The part 50 smoothly fits the wall of the opening 9 and the inner face of the nipple 10. The float 44 is arranged between the coils of the tube 49. 65

The float 44, the valve 22, the needle valve 37 70 which is a regulator and the block 33 coact to provide an automatic air release.

As the beer leaves the cooling coils it passes through the large opening 3 into the chamber 47 and that by virtue of the automatic air release beer arrangement air pockets are dispensed 75

with, therefore keeping the beer smooth, and by virtue of the normal beer pressure, the beer that is smooth is forced along through the restricted tube 49 directly to the beer faucet, maintaining an even beer, or in other words, this arrangement tends to dispense with wild beer conditions so that the vending of beer becomes simplified and free of waste at a very nominal cost. 5

The valve 22 is a tip point valve and acts as a release for the pressure built up when the fluid 10 enters the chamber 47 and for the discharge of any air pockets which might remain in the upper portion of the chamber 47 and thereby prevent complete filling with liquid.

The valve 37 is a utility valve that is kept open 15 at all times during the drawing of beer, and is employed so that when a barrel of beer is empty it can be closed down preventing the escape of carbonic gas. It is an added precaution which enables the bartender or whoever is handling the 20 beer to turn it off in his coil box without going to the point where the main valves are located to shut off such valves.

What I claim is:

1. In a draught beer controller, means providing an upstanding closed beer settling chamber and a pair of oppositely extending laterally disposed spaced nipples in proximity to the top of said chamber, one of said nipples being of greater inner diameter than the other constituting an intake for said chamber and adapted to be connected to and permanently open into the cooling coil portion of a beer dispensing line, the other one of said nipples adapted to be connected to the discharge portion of the beer dispensing line, 35 and a restricted upstanding coiled tubular element suspended within said chamber for conducting off the beer received therein, said element having a permanently open lower end disposed in the lower portion of said chamber constituting an intake for said element and a flared upper terminal portion constituting an outlet for said element adapted to permanently communicate with the discharge portion of such line and positioned within and disposed at the outer end of the nipple of smallest inner diameter, and said element having a substantially laterally disposed upper part extending from said chamber into the nipple of smallest inner diameter and merging into said flared upper terminal portion, 40 the inner diameter of said element at its intake end being less than the inner diameter of the nipple of greatest inner diameter, the inner diameter of the said part being less than the inner diameter of the nipple of greatest diameter. 45

2. In a draught beer controlling means, an open top and closed bottom container providing a beer settling chamber formed near its top with a permanently open intake, a closure for closing the open top of the container, a coiled tubular beer conducting off element providing a restricted passage for the beer suspended within said chamber and having a lower open end forming an intake for said element below the intake for said chamber and an open upper end terminal portion providing an outlet for said element, said chamber having an upper outlet providing an extension disposed exteriorly thereof and said open upper end terminal portion of said coiled element leading into said outlet extension, a vertically movable float within said chamber confined by coils of said coiled element, and an air releasing means depending into said chamber, said means having its operation controlled by said float. 60

3. In a draught beer controlling means, an 65

open top and closed bottom container providing a beer settling chamber formed near its top with a permanently open beer intake, a closure attached to the container for closing the open top of the latter, a coiled upstanding tubular restricted beer conducting off element suspended within said chamber and having a free lower open end forming an intake for said element below the intake for said chamber and a fixed flared 10 open upper end terminal portion providing an outlet for said element disposed exteriorly of said chamber, said element having an upper part

extended from said chamber and merging into said upper terminal portion, a vertically movable float within said chamber confined by coils of said element, and an air releasing means carried by said closure depending into said chamber, engageable by, free of connection to and having its operation controlled by said float, the said air releasing means including a pivoted lever member disposed within said chamber having an end portion permanently bearing on the upper end 10 of the float.

FRED C. BRISTOL.
